his attorney.

UNITED STATES PATENT OFFICE.

ROBERT D. HAYES, OF NEW HAVEN, CONNECTICUT, ASSIGNOR TO INDEX VISIBLE,
INCORPORATED, OF NEW HAVEN, CONNECTICUT, A CORPORATION OF NEW YORK.

INDEX OR FILE.

Application filed October 16, 1915. Serial No. 56,304.

To all whom it may concern:

Be it known that I, ROBERT D. HAYES, a citizen of the United States, residing in the city and county of New Haven and State of Connecticut, have invented certain new and useful Improvements in Indexes or Files, of which the following is a full, clear, and exact description.

This invention relates to indexes or files, and it has particular reference to a so-called visible index embodying a plurality of record holding members or cards which, in the normal position, are held in overlapped relation so that only the marginal portions thereof are exposed to view. The invention also has special reference to a system of this kind in which each card is held flatwise on a support by a tongue or tongues on the card, as shown, for example, in the Fisher Patent No. 1,048,056, dated December 24, 1912, although it may be used to advantage in connection with other record systems.

One of the primary objects of the present invention is to provide means for protecting the cards and preventing excessive wear thereof, while at the same time providing for the full visibility of the record matter and the manual manipulation of the cards incident to their application to, and removal from, the support. To this end, each card is provided with a cover of celluloid or other transparent material constructed in the manner hereinafter described.

Another object of the invention is to provide a record member or card having a protective sheath which is shiftable on the card, while the latter remains in place on a suitable support, so that matter may be written on the card proper, or on a record slip or insert carried thereby, without the necessity of removing the card from the support. This is an especially important feature of my invention, because the index or file is thereby made much more convenient than in the case where each record card or slip has to be bodily removed from the support or guide before the protective sheath can be even partly removed.

To these and other ends, the invention consists in the novel features and combinations of parts to be hereinafter described and claimed.

In the accompanying drawing,
Fig. 1 is a fragmentary front elevation

of an index or file embodying my improvements;

Fig. 2 is a front elevation of two of the record members nested together but removed from the support;

Fig. 3 is an enlarged end elevation of the parts shown in Fig. 2;

Fig. 4 is a front view, partially broken away, of a modified form of record member; and

Fig. 5 is an enlarged section on line 5—5 of Fig. 4.

Referring to the drawing, I have shown a plurality of cards 6 constructed of pasteboard and provided with integral tongues 7, whereby the several cards are nested together in overlapped relation with their upper margins exposed. The tongues 7 also serve to engage a support or guide in the form of a strip 8, substantially as disclosed in Fisher Patent No. 1,048,056, dated December 24, 1912. Each card or member 6 is provided with a protective sheath 9, preferably of celluloid or similar transparent material, which extends across the front face of the card and protects the latter, together with the record matter carried thereby, without, however interfering with the visibility of such record matter.

In the form shown, the sheath 9 is constituted by a celluloid strip of approximately the same length and height as the card, having a turned over flange 10 extending around and behind the top edge of the card, and a similar flange 11 extending around and behind the bottom edge of the card. The flanges 10, 11 form

in effect guides for the top and bottom edges of the card 6, the construction being such that while the card is held on the support 8 by means of the tongues 7, the sheath or cover may be moved wholly or partially off the card, as shown at the lower part of Fig. 1. Preferably, the ends of the sheath are provided with cut-out portions 12 which enable the end portions of the card to be readily grasped when desired, and preferably also suitable stops will be provided for preventing displacement of the sheath with respect to the card, under ordinary conditions.

In the form shown, the sheath is provided with small end flanges 13, as shown more particularly in Fig. 3, these flanges being made integral with the celluloid body of the sheath, and being extended across the re-

- spective ends of the card. In this manner, the sheath is prevented from jarring off the card or being accidentally displaced, but when it is desired to shift the sheath or cover 5 lengthwise of the card in order to expose the surface of the card for writing thereon, this can still be done irrespective of the end flanges 13, which do not offer sufficient resistance to prevent this shifting movement.
- 10 In order to permit the manipulation of the tongues 7 from the front of the card, the sheath 9 is provided with apertures or openings 14 which are substantially in registry with the respective tongues when 15 the parts are in the normal position. By this arrangement, the fingers of the operator may be engaged with the tongues in such a manner as to fasten the latter on and remove them from the supporting strip 8.
- 20 It will be observed from Fig. 3 that the tongues of each card serve to receive and support the lower edge of the sheath of the card next above it. A series of cards may be placed in nested relation and manipulated 25 with respect to each other and the support without any inconvenience being caused by the provision of the protective sheaths or covers. In the form shown in Figs. 1, 2 and 3, the record matter is written 30 directly on the body of the card, and when it is desired to add new matter or to change the matter already on the card, it is simply necessary to shift the cards so as to isolate the one desired, as shown at the lower part 35 of Fig. 1, after which the sheath of the desired card can be moved either to the right or to the left so as to expose that portion of the card to which access is desired.
- In the form shown in Figs. 4 and 5, the 40 dimensions of the card 6^a and sheath 9^a are somewhat different from the corresponding elements shown in Figs. 1 to 3, although the principle is the same. Here, however, a record slip or insert 15 of comparatively thin 45 paper is interposed between the body portion of the cover or sheath and the front surface of the card proper, and the record matter is written directly on this slip or insert instead of on the card proper, although it will be understood 50 that record matter may also be placed upon the card 6^a itself if desired, as well as upon the insert. That is to say, either one or both of these elements may be used for the reception of reference material. In this 55 particular case, the end stops on the sheath are omitted, and the record-carrying surface is much larger than in Figs. 1-3, on account of the dimensions of the card and the fact that the slip or insert is imperforate.
- 60 It will be observed that the transparent sheath, which extends over substantially the entire area of the front face of the card, and is attached to the latter at the upper and 65 lower edges of the card, forms a pocket on the

front of the card in which a record slip or insert can be readily inserted from the end of the card. An important advantage of my invention arises from the fact that this record slip or insert can be readily inserted 70 from the end of the card, while the latter is attached to the support. In other words, when the card is attached to the support, the pocket which is open at one or both ends of the card is readily accessible for the insertion of a record slip. This advantage is due to the fact that the card is provided with special means for attaching it to the support at points remote from the pocket ends. 75

Various changes in the details of the device 80 may be adopted without departing from the scope of the invention as defined in the claims.

What I claim is:—

1. In an index or file, a support, a record 85 member detachably connected therewith, and a protective cover for said record member displaceable thereon without detaching said record member from said support; substantially as described.

2. In an index or file, the combination of an elongated support, a record member slidably engaging the same, and a protective cover for said record member slidably thereon, while said record member is mounted 95 on said support; substantially as described.

3. In an index or file, the combination of a supporting strip, a card supported thereon, and a protective sheath for the card shiftable so as to expose a portion of the 100 latter; substantially as described.

4. In an index or file, a record card having means adapted to engage a support and having a transparent cover displaceable relatively to the support; substantially as 105 described.

5. In an index or file, a card having an attaching tongue, and a protective sheath for said card cut away to permit the manipulation of said attaching tongue; substantially 110 as described.

6. A record member for indexes or files, comprising a card having a tongue cut from the body portion thereof, and a protective sheath for the card having an opening to 115 register with said tongue; substantially as described.

7. A record member for indexes or files, comprising a card having a plurality of tongues adapted to engage a support, and 120 a protective sheath engaging the top and bottom edges of the card and having openings adapted to register with said tongues; substantially as described.

8. A record member, comprising a card, 125 attaching means carried by the card at the rear portion thereof, and a protective sheath covering the front portion of the card; substantially as described.

9. In an index or file, the combination of 130

- an upright support, a card secured on said support so as to move vertically thereon, and a protective sheath for the card movable laterally of the support; substantially as described.
10. In an index or file, the combination of a card, means guiding said card for movement in one direction, and protective means 5000
slidable on the card in a direction at right angles to the first-named direction; substantially as described.
11. In an index or file, the combination of a plurality of cards, means nesting said cards together flatwise with their margins exposed, and protective sheaths movable lengthwise of the cards; substantially as described.
12. In an index or file, the combination of a card, a protective sheath therefor, means carried by the card for attaching it to a support, and a record slip or insert interposed between the sheath and the card; substantially as described.
13. The combination with a record card, of a sheath slidable thereon, said sheath having finger-receiving openings formed therein, and means for limiting the sliding movement of the sheath with respect to the card; substantially as described.
14. The combination with a card having attaching tongues, of a protective sheath engaging the upper and lower edges of the card, and having openings adapted to register with said tongues; substantially as described.
15. In an index or file, a card or member having a tongue projecting therefrom, a sheath adapted to fit in the space between said tongue and the body of the card, and a second card enclosed by said sheath; substantially as described.
16. In an index or file, the combination of a support, a plurality of cards mounted flatwise thereon, each individually insertable and removable without removing the others, and a protective sheath mounted to slide on each card while the card is mounted on said support; substantially as described.
17. In an index or file, a support, a record member, a transparent cover member for said record member, means for attaching one of said members to said support, the other member being displaceable relatively to the first without detaching said first member from said support; substantially as described.
18. In an index or file, a support, a record member, a protective cover member for said record member, and means for attaching one of said members to said support, the other member being laterally shiftable relatively to the first member for exposing the face of said record member; substantially as described.
19. In an index or file, a support, a record member detachably connected therewith, and a transparent cover member for said record member displaceable laterally of said support to expose the face of said record member without detaching said record member from said support; substantially as described.
20. In an index or file, a guide, a record member, a protective transparent cover member for said record member, means for securing one of said members to said guide so that it is movable relatively thereto, the other member being movable relatively to the guide without detaching the first member therefrom, whereby the face of said record member may be exposed; substantially as described.
21. In an index or file, a record member, and a cover member slidably mounted on said record member having finger-receiving openings formed therein; substantially as described.
22. In an index or file, a card having an attaching tongue, and a protective sheath slidably mounted upon said card; substantially as described.
23. In an index or file, a support, a card movable on the support, and a pocket extending across one face of the card and open at its end for the insertion of a record slip.
24. In an index or file, a support, a card, having a pocket open at the end, movable thereon, and a record slip insertable into the pocketed card at the end opening thereof while the latter engages the support.
25. In an index or file, a transparent sheath member having rearwardly turned top and bottom retaining edges and means for attaching said sheath member to a support, so that the ends of the sheath member are open for the insertion of a record slip without disengaging said sheath member from the support.
26. In an index or file, a transparent sheath member having a pocket at the rear face of the same and open at both ends, and means for attaching said sheath member to a support at a point remote from the open pocket ends.
27. In an index or file, a card having means for engaging a support and a transparent cover member on the front face of said card covering substantially the card from top to bottom and presenting a pocket open at the end of the card.
28. A sheath for the purpose described, having a transparent front wall and provided with a tongue at the rear side thereof, a plurality of such sheaths being adapted to be nested together with an edge of one sheath disposed between the tongue and body of the adjacent sheath.
29. A sheath adapted to receive and

- cover a separate reference slip and having a transparent front wall through which matter on the reference slip can be read, a tongue at the rear of the sheath whereby a plurality of said sheaths can be interlocked with one edge of one sheath extending between the body and tongue of the next sheath, said tongue being secured to the body of the sheath at a point between the longitudinal edges of the sheath and thus limiting the distance that the next sheath can extend between the body and tongue of the sheath.
30. In a device of the character described, a series of sheath elements, each adapted to receive and cover a separate reference slip and having a transparent front wall through which matter on the slip can be read and having a part projecting rearwardly substantially in the plane of said sheath from a portion thereof, said elements being assembled with a portion of each element extending between the sheath and projecting part of the next element.
31. In a device of the character described, a series of open-ended sheaths each adapted to receive and cover a separate reference slip and having transparent front walls through which matter on the slips can be read, and each having a thin longitudinal edge and a tongue at the rear of the body of said sheath extending from said thin edge toward the opposite edge of the sheath, and means for retaining said sheaths in parallel relation with the thin edge of each sheath extending between the body and the tongue of the next sheath.
32. In a device of the character described, a series of sheath elements each adapted to receive and cover a separate reference slip and having a transparent front wall through which matter on the slip can be read, and having a part projecting rearwardly substantially in the plane of said sheath adjacent one longitudinal edge thereof, said ele-
ments being assembled with the upper portion of each element extending between the sheath and projecting part of the next element, said sheath elements having stops between their edges which limit the distance that one sheath extends between the parts of the other sheath.
33. In an index or file, a support, a series of nested overlapping sheaths thereon, each sheath having a transparent front wall and being adapted to receive a reference slip.
34. In an index or file, a support, a series of nested overlapping sheaths thereon, each of said sheaths having a transparent front wall and means upon one sheath engaging an adjacent sheath to maintain them in relative positions.
35. In an index or file a sheath comprising a pocket with a transparent front wall and a tongue projecting rearwardly approximately in the plane of said sheath, whereby a similar sheath is adapted to be received between the tongue and body of that sheath.
36. In an index or file, a support, a series of sheaths attached thereto, each comprising a pocket for a record member, having a transparent front wall and a tongue provided at the rear of the sheath, said sheaths being assembled with one of the longitudinal edges of one disposed between the tongue and body of an adjacent sheath.
37. In an index or file, a sheath having a transparent front wall and a tongue at the rear thereof, said tongue being accessible for manipulation from the front of the sheath.
38. In an index or file, a card provided with a tongue, a transparent member mounted on said card and covering a portion of the face thereof but leaving uncovered a part of the card adjacent said tongue.
- In witness whereof, I have hereunto set my hand on the 15th day of October, 1915.

ROBERT D. HAYES.
